R. FERRO

STOCK AND DIES WITH OILING DEVICE

Filed Feb. 20, 1925

UNITED STATES PATENT OFFICE.

ROCCO FERRO, OF UTICA, NEW YORK.

STOCK AND DIES WITH OILING DEVICE.

Application filed February 20, 1925. Serial No. 10,555.

My present invention relates to a stock and dies having combined therewith an oiling device.

The purpose of the invention is to provide an improved, convenient and effective oiling device for a stock and dies.

A further purpose is to provide an oiling device in the combination suggested in which the valve controlling the supply of oil to the dies can be so readily opened and closed that the user of the tool will open the valves when starting to use the tool and close them when he has finished the cutting operation.

A further purpose is to provide an oiler of the class described having means for adjusting the position of the valve at its open position to get the correct flow of oil which adjustment will not be disturbed by the regular opening and closing of the valve at the beginning or end of the use of the tool.

Further purposes and advantages of my invention will appear from the specification and claims herein.

Fig. 1 is a view of a stock and dies equipped with the oiling devices embodying my invention, said view being in the main a plan view of the tool but with parts adjacent one oiling device, air vent tube and filler plug shown in section.

Fig. 2 is a detail sectional view of the joint between the cap plate and the adjacent wall.

Referring to the drawings in a more particular description it will be seen that the tool comprises a stock having sockets or slideways 11 to hold the dies 12 in position to cut the threads upon the pipe when the stock is rotated by its outwardly projecting handles 13.

In the drawing I have shown the tool equipped with two oiling devices. In the device shown in the upper left-hand part of Fig. 1 the oil is led towards the pipe through a tube 14 which projects into the side of the die and then through the center of the die toward the pipe being cut, this die being slotted from its rear on the side towards the tube 14 and then provided with a hole through the center of the die extending to the inner or pipe engaging end of the die. In the oiling device as shown in the lower right-hand part of Fig. 1 the oil duct 15 leading from the reservoir 16 is in direct connection with a short tube 14^a extending radially inward to a point just ahead of the adjacent die 12. It will be seen that my oil-

ing device can be used effectively with either of the illustrated modes of conducting oil to the dies or with any other form where the duct or tube conducting the oil to the die can be provided with the valve and other co-operating parts of my invention.

Conveniently housed upon the frame or casing 10 of the stock there are provided one or more reservoirs 16. These reservoirs may be conveniently formed and preferably will be formed as an integral part of the frame 10 by providing a deep pocket between two adjacent die-holding sockets 11 with the face of the pocket adapted to receive and have secured thereto a cap plate 17 to complete the reservoir. In the upper left hand portion of Fig. 1 the reservoir is shown entirely without the cap plate but in the lower right hand portion of Fig. 1 the reservoir is shown with a cap plate in place but with the central part of the said plate removed in order to show the parts within the reservoir.

In the inner wall of the reservoir or near one of the inner corners of the reservoir according to which of the two types of feeder tubes 14 or 14^a is to be used, there is provided a duct 15 leading to the tube 14 in the one case or to the tube 14^a in the other case. The reservoir end of this duct 15 is preferably shaped to tapering form to provide a proper valve seat for the point 18^a of the needle valve 14^a. This needle valve consists of a spindle 18 extending from the duct 15 through the cavity of the reservoir and then through a housing 19 set into the outer wall 20 of the receptacle to a point entirely without the receptacle 16.

The spindle 18 of the needle valve is slidably mounted in the housing 19 so that said needle valve may be moved to open or closed position relative to the duct 15. The housing 19 will conveniently be secured in the outer wall 20 of the reservoir by having said housing screw-threaded into a suitable hole provided in the said wall 20. Near the inner end of the housing 19 there is provided an oil-tight packing between the bore of the housing 19 and the spindle 18. Such packing consists of a metal annular disk 21, a packing ring 22 of any desired fiber or material and an outer annular ring 23. On the inner side of the inner ring 21, that is toward the inner end of the needle valve, there is thrust through the spindle a pin 24, the short projecting ends of which keep these packing rings in place upon the spindle and

also allow these packing rings to form a stop for the inner end of the tension spring 25 coiled about the spindle 18. A bonnet 26 is screw-threaded onto the end of the housing 19 without the outer wall 20 of the reservoir. A hole through the cap portion of this bonnet allows the outer end of the spindle 18 to project therethrough while the inner face of the bonnet provides a stop for the outer end of the coil spring 25. From this construction it results that the spring yieldingly forces the needle valve to closed or seated position. The valve is readily retracted against the tension of spring 25 by means of a short rock or cam lever 27 having forked ends 28 which straddle the outwardly projecting end of the spindle 18 and are pivotally fastened thereto by pin 29. The outer extremities of the forked ends 28 of the rock or cam lever 27 are adapted to make contact with the adjacent outer end or top surface of bonnet 26 when said lever is rocked to cam or retract the needle valve 18 to open position against the spring 25 which position of the parts is clearly shown in the valve in the lower right hand part of Fig. 1. The distance from the axis of the pin 29 to the squared extremities of the forked lever ends 28 is greater than the distance from the axis of the said pin to the sides of the lever 27 so that when the lever 27 is swung to a right angle relative to the spindle 18 the needle valve may be forced by the spring to closed position as shown by the valve in the upper left hand part of Fig. 1 but when the lever 27 is swung outwardly into alignment with the spindle 18 said spindle is retracted and the needle valve opened. The tension of the spring draws the squared extremities of the forked ends 28 tightly enough towards the bonnet 26 to hold said snap lever 27 in its aligned position against accidental displacement.

It will now be seen that the operator may readily open or close the valve by simply swinging this snap lever 27 to upright or downward position. This operation is much easier and quicker than any screw adjustment and moreover has the advantage of giving a visible indication as to the position of the valve.

The distance that the needle valve is retracted from its seat in open position may be readily adjusted within a considerable limit by moving the screw-threaded bonnet 26 farther onto or off from the housing 19. For instance if it is desired that during a given cutting operation more oil be provided the bonnet 26 will be unthreaded slightly and this will operate to retract the needle valve proportionately more from its seat when the operating lever 27 is moved to aligned position. It will be particularly noted that this adjustment will not be dis-

turbed by the subsequent opening or closing of the needle valve. For a general line of work the valve will be set to a given position when opened by its operating lever and this adjustment will not be disturbed except as different conditions of work, oil or temperature require.

The reservoirs are provided with a filling aperture 30 located in the outer wall 20, these filling apertures being closed by plug 31. Each reservoir will also be provided with an air vent whereby air may be admitted to the reservoir from time to time as the oil is fed therefrom. Preferably this air vent will consist of an air vent pipe 32 having its inner end screw-threaded into a proper hole provided in the inner wall of the reservoir with the outer end of the pipe extending almost to the outer wall of the reservoir. Preferably the hole 33 into which this pipe 32 is threaded will be in alignment with the filling opening 30. This enables the hole 30 to be used to get access to the hole 33 during the manufacture of the tool and also results in the air vent pipe 32 being directly in alignment with the hole 30 so that the pipe 32 may be readily cleaned out when required by sticking a wire directly through said pipe by using the hole 30. Preferably a partition 34 extends from the front to the rear side of the recess so as to form a pocket in the portion of the recess next to the needle valve. This keeps a supply of oil near the needle valve through a larger portion of the rotation of the tool.

I have found that a convenient and effective way to form a substantially oil-proof joint between the front surface of the walls of the reservoir and the closing gap 17 is to form a substantially square recess 35 in the front face of the reservoir and to place in said recess a circular lead wire packing 37. This lead wire packing can be readily bent to the curves of the recess 35 around the reservoir when the closing plate 17 is placed in position and fastened to the casing of the tool by a plurality of round-headed screws 36. The plate will be forced down upon the lead tightly enough to effect a substantially oil-proof joint.

What I claim as new and desire to secure by Letters Patent is:

1. In a stock and dies the combination of a stock casing with outwardly extending means for mounting said dies, dies mounted therein, a reservoir for lubricating oil located within said casing between adjacent die-holding means, a duct leading from said reservoir inwardly toward the die, a longitudinally slideable needle valve, mounted in said casing and having its inner end adapted to block the opening through said duct and having its outer end extending without the casing, a spring operatively connected to said valve tending to keep it

yieldingly seated against said duct opening, and a swinging cam lever connected to said valve and manually operable from without the casing and adapted to be set at one position to hold the valve open against said spring tension, and adapted in its other position to allow the valve to close under said spring tension and means interposed between said swinging lever and the 10 casing and operative from without the device for varying the open position of the valve, such adjustment not being disturbed by the regular closing and opening of the valve by said swinging lever.

15 2. In a stock and dies the combination of a stock casing with outwardly extending means for mounting said dies, dies mounted therein, a reservoir for lubricating oil located within said casing between adjacent die-holding means, a duct leading from said reservoir inwardly toward the die, a longitudinally slideable needle valve, mounted in said casing and having its inner end adapted to block the opening through said 20 duct and having its outer end extending without the casing, a spring operatively connected to said valve tending to keep it yieldingly seated against said duct opening, and a swinging cam lever connected to said valve and manually operable from without the casing and adapted to be set at one position to hold the valve open against said spring tension, and adapted in its other position to allow the valve to close under 25 said spring tension and screw-threaded means interposed between said swinging

lever and the casing and operable from without the device for varying the open position of the valve, such adjustment not being disturbed by the regular closing and 40 opening of the valve by said swinging lever.

3. In a stock and dies the combination of a stock casing with outwardly extending means for mounting said dies, dies mounted 45 therein, a reservoir for lubricating oil located within said casing between adjacent die-holding means, a duct leading from said reservoir inwardly toward the die, a longitudinally slideable needle valve, 50 mounted in said casing and having its inner end adapted to block the opening through said duct and having its outer end extending without the casing, a spring operatively connected to said valve tending to 55 keep it yieldingly seated against said duct opening, and a swinging cam lever connected to said valve and manually operable from without the casing and adapted to be set at one position to hold the valve open 60 against said spring tension, and adapted in its other position to allow the valve to close under said spring tension and an air vent tube extending from the portion of the reservoir remote from the die through the 65 wall of the reservoir nearest the center of the die stock and a filling plug on the outer side of the reservoir.

In witness whereof I have affixed my signature, this 22 day of January, 1925.

ROCCO FERRO.
